UNITED STATES PATENT OFFICE

156,918

CARRYING CASE FOR PHOTOGRAPHIC LIGHT METERS

Harry Rosenthal, Mount Vernon, N. Y.

Application December 15, 1948, Serial No. 150,177

Term of patent 3½ years

(Cl. D61—1)

To all whom it may concern:

Be it known that I, Harry Rosenthal, a citizen of the United States, residing at Mount Vernon, in the county of Westchester and State of New York, have invented a new, original, and ornamental Design for a Carrying Case for Photographic Light Meters, of which the following is a specification, reference being had to the accompanying drawing, forming a part thereof.

In the drawing:

Fig. 1 is a front perspective view of a carrying case for photographic light meters, showing my new design;

Fig. 2 is a similar view in partially open position;

Fig. 3 is a similar view showing the carrying

case for photographic light meters in fully open position; and

Fig. 4 is a vertical sectional view taken on the line 4—4 of Fig. 3.

I claim:

The ornamental design for a carrying case for photographic light meters, as shown.

HARRY ROSENTHAL.
